(57) **CLAIM**

The ornamental design for a lighting fixture, as shown and described.

DESCRIPTION

FIG. 1 is an isometric view of a lighting fixture.

FIG. 2 is an enlarged view of a portion of the lighting fixture as shown in FIG. 1.

FIG. 3 is a bottom view of the lighting fixture of FIG. 1.

FIG. 4 is an enlarged view of a portion of the lighting fixture as shown in FIG. 3.

FIG. 5 is a side view of the lighting fixture of FIG. 1.

FIG. 6 is an enlarged view of a portion of the lighting fixture as shown in FIG. 5.

FIG. 7 is another side view of the lighting fixture of FIG. 1.

FIG. 8 is another side view of the lighting fixture of FIG. 1.

FIG. 9 is another side view of the lighting fixture of FIG. 1.

FIG. 10 is a top view of the lighting fixture of FIG. 1.

FIG. 11 is a cross-section view of the lighting fixture along the line 11-11 in FIG. 3; and,

FIG. 12 is an enlarged view of a portion of the cross section of the lighting fixture as shown in FIG. 11.

The broken lines in the drawings denote structure that is not part of the claimed design.

1 Claim, 10 Drawing Sheets
